FLUID LIFT PUMP

Addie Kinch Wade, Jr., San Diego, Calif.

Application November 1, 1943, Serial No. 508,598

2 Claims. (Cl. 103—232)

This invention relates to fluid lift pumps of the air pressure type, and has more particular reference to an improved foot piece for such a pump.

The primary object of the present invention is to provide, in a fluid lift pump of the air pressure type, a foot piece of simple and durable construction which may be conveniently and economically manufactured, and which will operate efficiently for the intended purpose.

The invention consists in the novel form, combination and arrangement of parts hereinafter more fully described, shown in the accompanying drawing and claimed.

In the drawing, wherein like reference characters indicate corresponding parts throughout the several views:

Figure 1 is a view, partly in vertical section and partly in elevation, showing a fluid lift pump positioned in a well tubing and having a foot piece constructed in accordance with the present invention.

Figure 2 is an elevational view of the foot piece.

Figure 3 is a central vertical sectional view of the foot piece shown in Figure 2.

Figure 4 is a horizontal section taken on line 4—4 of Figure 3.

Figures 5—7 are diagrammatic views of modified structures.

Referring in detail to the drawing, 10 designates generally a conventional well tubing having an outlet 11 near its top.

The fluid lift pump is adapted to be positioned in the well tubing 10 with the foot piece 12 positioned adjacent the bottom of the tubing 10. As shown, the foot piece 12 includes a relatively long air supply pipe section 13 having a side opening 14 near its lower end, a shorter air discharge pipe 15 disposed parallel to and rigidly secured throughout its length, preferably by welding, as at 16, in contact with the lower end portion of the air supply pipe section 13 at one side of the latter. The air discharge pipe 15 comprises a straight pipe section having a side opening 17 registered with the side opening 14 of the air supply pipe section 13. The pipe section 13 is open at the top and externally threaded at its upper end, as at 18, to facilitate connection of another pipe section 19 therewith by means of a coupling 20. The air discharge pipe 15 is also open at the top, and the lower ends of the pipe section 13 and the pipe 15 are suitably closed, such as by means of threaded closure plugs 21 and 22, respectively.

It will be apparent that the present foot piece may be readily and economically manufactured

by simply providing two pipe sections of the required different lengths, forming the openings 14 and 17 in them, placing the two pipes in proper side-by-side relation, and then welding them together, the closures 21 and 22 being duly inserted and the upper end of the pipe section 13 being duly threaded at 18. The foot piece is of very rigid and durable construction, as will be evident.

While I have specifically illustrated and described a foot piece having a single air discharge pipe 15, it will be apparent that additional air discharge pipes may be similarly associated with the pipe section 13 in grouped relation about the latter, as diagrammatically shown in Figures 5 to 7, inclusive. As this is mere duplication, specific illustration and description thereof is deemed unnecessary. Also, while the pipes have been referred to as air supply and discharge pipe, it will be understood that steam or any other gaseous pumping medium under pressure may be used in lieu of air.

In operation, the air or other gaseous pumping medium under pressure is supplied to the pipe section 13 from any suitable source, and this pumping medium will pass through the openings 14 and 17 into and upwardly from the discharge pipe 15 beneath the column of liquid within the well tubing. In this way, the column of liquid in the tubing 10 will be forced upwardly and discharged through the outlet 11. While the device has been described as a pump, it is to be understood that the invention is capable of other uses where a pressure device of this general kind is employed. Minor changes in details of construction are contemplated such as fall within the spirit of the invention as claimed.

What I claim is:

1. A foot piece for a fluid lift pump of the air pressure type, comprising a relatively long air supply pipe section having a side opening near its lower end, a shorter air discharge pipe disposed parallel to and rigidly secured throughout its length to and in contact with the lower end portion of said air supply pipe section at one side of the latter, said air discharge pipe comprising a straight pipe section having a side opening registered with the side opening of the air supply pipe section and being open at the top, a closure for the lower end of said air supply pipe section, and a closure for the lower end of said air discharge pipe.

2. The construction defined in claim 1 wherein the air supply pipe section and the air discharge pipe are welded together along opposite sides of their line of contact.

ADDIE K. WADE, Jr.
